ATTORNEYS

UNITED STATES PATENT OFFICE.

JOHN KLEIN, OF TAMPA, FLORIDA.

SEAL.

1,127,020.

Specification of Letters Patent. Patented Feb. 2, 1915.

Application filed September 12, 1914. Serial No. 861,397.

To all whom it may concern:

Be it known that I, JOHN KLEIN, a citizen of the United States, residing at Tampa, in the county of Hillsborough and State of Florida, have invented a new and useful Improvement in Seals, of which the following is a specification.

This invention relates to seals, and more particularly to a combined seal and name plate for use on trunks, suit cases, and articles of a similar nature.

One of the principal objects of the invention is to provide a seal of the class described which is capable of quick and easy manipulation, and which will hold the article to which it is attached firmly locked and secure against undetected tampering.

Another object of the invention is to provide a seal which may be readily unlocked without the use of a tool.

Still another object of the invention is to provide a seal in which a metallic sealing strip is utilized for locking the members of the seal together, thus maintaining the article to which the seal is attached in locked position, said sealing strip being capable of being broken by the fingers for unlocking the seal.

A still further object of the invention is to provide a seal of the class described which will be simple, durable, efficient in operation and inexpensive to manufacture.

With these and other objects in view which will become apparent as the description proceeds, the invention resides in the construction, combination and arrangement of parts, hereinafter more fully described and claimed, and illustrated in the accompanying drawing, in which like characters of reference indicate like parts throughout the several figures, of which—

Figure 1 represents a front elevational view of a seal constructed according to my invention showing the same in locked position, the spring holding case being shown in section. Fig. 2 represents a vertical transverse sectional view taken on the plane indicated by the line 2—2 of Fig. 1. Fig. 3 represents a front elevational view of the case the sealing strip being indicated in position therein. Fig. 4 represents a horizontal sectional view taken on the plane indicated by the line 4—4 of Fig. 1, and Fig. 5 represents a perspective view of the sealing strip.

Referring more particularly to the drawing the seal is shown as applied to a suit case, 5 indicating the top and 6 the body

thereof. The seal comprises a casing 7 secured to the body, a staple 8 secured to the top and a sealing strip 9 adapted to connect the staple and casing for locking parts of the suit case together, suitable means being provided as hereinafter described for attaining a locking engagement of the strip with the staple and casing.

The casing is hollow, and is provided with flanges 10 whereby it may be secured to the suit case by means of rivets or similar fastenings 11. The front and rear walls of the casing are provided with inwardly extending vertical channels 12, which extend from the top nearly to the bottom of the casing. The channels serve mainly to guide the sealing strip. Secured within the casing 7 are the leaf springs 13, which are disposed one in each end of the casing on opposite sides of the channels. The springs each comprise a leaf 14 and a shank or body 15. The latter is disposed in a substantially vertical position, and is secured at its outer end and also at a point near the junction of the shank and the leaf, to one of the end walls of the casing. The leaf portions of the springs extend obliquely downwardly toward each other from the upper corners of the casing, in the position shown in Fig. 1.

The sealing strip comprises a body 35 having guide flanges 16 projecting from one side thereof in parallel relation, and having a head 17 at its upper end and a finger hold 18 at its lower end. The head 17 is connected to the body by means of a neck 19 formed by notching the strip on its opposite edges as at 20. The wings or ends 21 of the head 17 project laterally from and overhang the edges of the strip.

In locking the device the strip is extended through the staple 8 and into the casing between the channels 12, in such position that the flanges 16 embrace the channel formed in the rear wall. The top and bottom walls 22 and 23 of the casing are provided with openings alining with the space between the channels, so that the strip may be extended through said walls. By forcing the strip down to the position shown in Fig. 1 the ends of the leaf springs are engaged by finger hold 18 and separated until said hold has passed below the lower ends of the springs, whereupon they retract to be engaged in the notches 24 cut in the edges of the sealing strip just above the finger hold. The notches form shoulders 25 against which the ends of the springs are

adapted to engage. This position of the strip is indicated in Fig. 1, and it will be evident that the strip cannot be raised out of engagement with the springs 4 without either breaking the strip or the springs and that by reason of the engagement of wings 21 of the head 17 with staple 8, the strip cannot be withdrawn from the bottom of the casing. When it is desired to unlock the seal the head is twisted by the fingers of the operator so as to sever it from the strip at the neck portion 19, and said strip may then be withdrawn by grasping the finger hold 18. The heads of the sealing strips are individually marked or numbered, so that if the seal should be broken by a person and another seal substituted the fact will be readily detected. Secured upon the front face of the casing is a plate 26 adapted to receive a visiting card, the plate being provided with the usual openings 27 to reveal the name and address on the card.

Such a seal as I have provided may be easily and quickly attached either to the side or the ends of a suit case or similar article, and may be quickly locked in position, and will maintain the suit case or trunk in securely locked position. A number of the sealing strips may be conveniently carried by a traveler, since they are small and of no material weight. The seal may be unlocked without the use of any kind of tool, by merely twisting and removing the head and withdrawing the sealing strip. This is an extremely advantageous provision, since it eliminates both the necessity of carrying a cutting tool, and the loss of time, disadvantages accruing to many of the seals heretofore provided.

Although I have described the preferred embodiment of my invention, I may desire to make such changes in the construction, combination and arrangement of parts thereof as do not depart from the spirit of the invention and the scope of the appended claims.

I claim:—

1. A seal comprising a staple and a hollow casing adapted to be secured to the closure members of an article to be locked, oppositely extending channels projecting inwardly from the opposite walls of the casing, and extending from the top nearly to the bottom thereof, leaf springs secured in said casing and inclining downwardly and toward each other from the upper corners of the casing, a sealing strip provided with flanges, said strip adapted to be extended into the casing between the channels, said flanges adapted to engage one of said channels for guiding the strip, said strip provided with shoulders against which said springs are adapted to lock, and a head

formed integrally with the strip and adapted to engage the staple when the springs are in locking position, said head being capable of severance from the strip, and means whereby said strip may be removed from the casing upon severance of the head.

2. A seal comprising a casing and a staple adapted to be secured to the closure members of a receptacle, a sealing strip, said strip adapted to be projected through the staple into said casing, co-acting guide means between the strip and casing, springs supported within the casing, co-acting means between said springs and strip for preventing withdrawal from the strip in the casing in one direction, a head carried by the strip and adapted to engage the staple for preventing withdrawal of the strip in the opposite direction, said head being capable of severance from the strip for allowing withdrawal of the latter.

3. A seal comprising a staple and a casing, a sealing strip adapted to be projected through said staple in one direction into the casing, means on said strip for limiting the movement of the strip through the staple in that direction, means carried by the casing adapted to engage the strip for preventing removal of the same from the casing in the opposite direction, said movement limiting means adapted to be severed from the strip for allowing withdrawal of the same, and means whereby the strip may be withdrawn upon severance of the movement limiting means.

4. In a seal of the class described, a sealing strip, said strip comprising a body portion having guide flanges projecting from one side thereof in parallel relation, a head, a neck connecting the head with the body portion, said head adapted to be severed from the body portion at the neck, a finger hold, and shoulders formed on the strip.

5. A seal comprising a staple and a casing, a sealing strip adapted to be extended through said staple into said casing, shoulders formed on said sealing strip, springs carried by the casing and adapted to engage said shoulders to prevent withdrawal of said strip in one direction, co-acting means between the strip and staple for preventing withdrawal of the strip in the opposite direction, said means capable of severance from the strip to allow withdrawal of the same, and means formed on the strip whereby it may be withdrawn upon severance of first said means.

JOHN KLEIN.
